UNITED STATES PATENT OFFICE.

WILLIAM S. WALBRIDGE, OF PERRYSBURG, OHIO, ASSIGNOR TO THE OWENS BOTTLE COMPANY, OF TOLEDO, OHIO, A CORPORATION OF OHIO.

TOOTHBRUSH CONTAINER.

Application filed October 7, 1922. Serial No. 593,111.

To all whom it may concern:

Be it known that I, WILLIAM S. WALBRIDGE, a citizen of the United States, residing at Perrysburg, in the county of Wood and State of Ohio, have invented new and useful Improvements in Toothbrush Containers, of which the following is a specification.

My invention relates to containers for tooth brushes, and more particularly to glass containers in which new tooth brushes are placed on the market for sale.

An object of the invention is to provide a novel and practical means to maintain tooth brushes in a sanitary condition while they are on sale. To this end I provide a glass container especially designed for holding the tooth brush and displaying it, while retaining the brush in a closed or sealed container, which prevents the brush from being touched by prospective buyers, as well as protecting it from dust, dirt or other sources of contamination. In this manner the purchaser is assured that he is obtaining the brush in a sanitary condition, as well as being supplied with a convenient receptacle in which the brush may be kept after it has been purchased.

Other objects of the invention will appear hereinafter.

In the accompanying drawings:

Figure 1 is an elevation view of the container with the tooth brush therein.

Figure 2 is a similar view looking in a direction at right angles to that of Figure 1.

Figure 3 is a top plan view of the same.

Figure 4 is a section at the line IV-IV on Figure 2.

The container A is preferably made of glass and is of a size and shape to form a receptacle for the tooth brush B. The body of the container is approximately triangular in cross section and comprises the three side walls 5, 6 and 7. The outer faces 40 of these walls are preferably flat and are connected by curved portions 8, 9 and 10. The inner faces 11, 12 and 13 of the side walls may be made slightly convex, as shown, to more nearly conform to the shape of the brush. The brush bristles 14 fit snugly between the surfaces 11 and 12 which are divergent but more nearly parallel, owing to the curvature of the surfaces 11 and 12, than they would be if said surfaces were 50 flat. The surface 13 forms a support for

the back of the brush. The receptacle A terminates at its upper end in a neck portion 15 which is circular in cross section and is formed with screw threads 16 or other means for securing the cap 17. The cap is preferably provided with perforations 18 to permit the circulation of air within the container. The container A and brush B are approximately the same length. The brush handle preferably protrudes a short distance beyond the neck 15 for convenience in removing the brush. It will be noted that the upper end of the brush handle normally rests against the edge of the neck 15. By having the handle protrude, as shown, it may be readily pushed forward to a central position in the neck of the container, permitting it to be easily grasped between the thumb and finger for withdrawing the brush.

It will be noted that the wall 7 of the container is somewhat shorter than the walls 5 and 6, so that the interior of the container will more nearly conform to the shape of the brush and its handle, thereby holding the brush snugly and preventing rattling or movement of the brush within the container. At the same time the bristles of the brush are not distorted or compressed to an undesirable extent.

Although the container is especially designed for use while the brush is on sale and before it has been put into use, it will be understood that it forms a convenient container in which the user may keep the brush permanently or when traveling, etc. The perforated top permits sufficient circulation of air to permit the brush to dry if it has been placed in the container directly after being used. The container with its perforated top may also be used for other purposes by the purchaser after it has served its primary purpose of displaying the brush and preserving it in a sanitary condition up to the time of its purchase.

Modifications may be resorted to within the spirit and scope of my invention.

What I claim is:

1. A glass container for a tooth brush, comprising three walls triangularly arranged and of a length corresponding to that of the tooth brush to be held therein, the cross section of the interior of the container being approximately an isosceles triangle with one side less than the other sides and forming a substantially flat support for the

back of the brush, the inner faces of the longer sides being convexly curved and united by a curved surface of a width to space said sides sufficiently to prevent crowding the brush, the container terminating in a circular open end provided with means for the attachment of a closure cap.

2. A tooth brush holding bottle comprising an elongated main body portion of substantial triangular cross-section, one side of said main body portion having its inner face shaped and proportioned to provide a seat for the back of the brush and the other sides of the body portion tapering towards one another so that their inner faces closely overlie opposite sides of the bristle portion of the brush and thereby retain the brush from substantial lateral movement in the container.
- 10 3. A tooth brush holding bottle comprising an elongated main body portion of substantially triangular cross-section, with one side less in width than the other sides and shaped and proportioned to provide a seat

for the back of the brush and the wider 25 sides of the body portion tapering towards one another so that their inner faces closely overlie opposite sides of the bristle portion of the brush and thereby retain the brush from substantial lateral movement in 30 the bottle.

4. A packaged tooth brush comprising a bottle having an elongated main body portion of substantially triangular cross-section, a tooth brush therein, one side of said main body portion having its inner face shaped and proportioned to provide a seat for the back of the brush and the other sides of the body portion tapering towards one another so that their inner faces closely 35 overlie opposite sides of the bristle portion of the brush and thereby retain the brush from substantial lateral movement in the container.

Signed at Perrysburg, in the county of 45 Wood and State of Ohio, this 5th day of October, 1922.

WILLIAM S. WALBRIDGE.
